TOY PUMP

Howard F. Klauss, Pittsburgh, Pa.

Application January 24, 1939, Serial No. 252,577

3 Claims. (Cl. 103—87)

My invention relates to pumps, particularly (though not exclusively) to small motor-driven pumps—toy pumps for delivering small streams of water.

The pump of the invention is intended for service in displays that include miniature waterfalls, canals, toy water wheels, and the like. I have particularly in mind the displays that are sometimes used in store-window advertising, and the miniature landscapes and other ornamental displays that are so commonly provided beneath Christmas trees. Having mentioned these particular adaptations, it will be understood that numerous other uses will be found for my pump.

5 The motor-driven pump unit of the invention includes a cylindrical or tubular housing. More particularly, the housing consists in a dome-shaped shell of small diameter relatively to its height. In service the shell stands on end in the body or pool of water from which the desired stream is to be drawn, and the dome-like top of the shell rises above the surface of the water. The shell is transversely partitioned, providing a pump chamber in the lower, submerged end of the shell, and providing in the upper end a water-tight housing for an electric motor. The pump chamber includes an impeller, connected by a vertical shaft to the rotor of the electric motor above. An inlet and an outlet are provided for the pump chamber, and rotation of the impeller in known way draws a stream of water from the pool in which the unit stands and delivers it through said outlet. The pump chamber in the lower end of the shell is submerged in the pool or body of water from which the stream is drawn, with the consequence that the pump need not be primed; it is merely necessary to start or stop the electric motor in order to initiate or terminate the flow of the stream.

40 In structures of this sort the motor must be enclosed, to protect it from the liquid being pumped, and due to such enclosure of the motor the matter of heat dissipation becomes a problem. That is to say, in service the motor generates heat that must be dissipated, to save the motor from damage. It is also desirable, if not essential, that the stream delivered by the pump may be regulated; that the mechanical friction losses of the rotating parts be reduced to a minimum; that the structure be of simple and economical construction, and easy to assemble. With such problems and desiderata in mind, it will be understood that my invention consists in refinements and improvements in structural detail and organization.

A unit embodying the invention is illustrated in the accompanying drawing. Fig. I is a view of the unit in side elevation. Fig. II is a view of the unit in vertical section, on the plane II—II of Fig. I; and Fig. III is a view of the same in cross section, on the plane III—III of Fig. II.

Referring to the drawing the dome-shaped shell that houses the structure is shown at 1. The shell includes top and bottom walls 2 and 20 and two intermediate walls or partitions 3 and 4; between bottom wall 2 and partition 3 a pump chamber 5 is formed, and between partition 4 and top wall 20 is a chamber 6. A rotary pump impeller 40 is arranged in chamber 5, while in chamber 6 an electric motor 7—in this case an induction motor—is mounted and enclosed. Above the partition 4, bracket portions 70 are provided on the wall of the shell for the mounting of the motor. The shell 1, partitions 3 and 4, and bracket portions 70 may be formed as a single casting, say 20 an aluminum casting, or the shell alone may be formed by "spinning" a sheet of metal (aluminum, brass or copper), and the partitions separately formed and sealed in position in the shell. Preferably, I make the shell, partitions, and 25 brackets integrally, in two sections 1a and 1b, as shown in the drawing, this practice permitting economical production in known die-casting apparatus. The two sections, thus accurately fashioned in dies, are adapted to meet edge to edge on a medial, axial plane of the assembly, and the meeting edges of the shell sections (including the diametrical edges of the semi-circular partition portions carried thereby) may be fashioned to provide a snug tongue-and-groove, or 30 lap-seam, union 8 of the parts. Security of assembly is obtained by means of cross-bolts 9.

The electric motor 7 is provided with an elongate drive-shaft or stem 10, extending vertically downward from its armature 1a, through partitions 4 and 3, and into the pump chamber 5. To the lower end of such shaft the rotary pump impeller 40 is secured. The impeller consists in a circular body portion 41 extending in a plane normal to the shaft 10, and carrying impeller 45 vanes 42 on its nether face. The inlet of the pump consists in a port 12 provided in the center of the bottom wall or floor 2 of the structure, and the shell 1 is provided with feet 13 that support the unit, with the floor 2 positioned above 50 the bottom but below the surface of the pool of water in which unit stands. The outlet 14 of the pump opens through the peripheral wall of chamber 5, and extends through a boss 15 that is integral with the housing 1 and internally 55

threaded for the attachment thereto of a pipe or hose (not shown). When the motor 7 is energized, and in consequence the impeller 40 rapidly rotated, water is drawn inward through port 12 and delivered through outlet 14.

The wall of the dome-like housing 1 includes a fitting 16 that permits the introduction of lubricant to the motor; the electric lead-wires 17 of the motor pass through a seal 18 in such wall; and it should be noted that the fitting 16 and seal 18 are water tight.

In accordance with the invention, I provide a large body of circulating water for cooling the motor, and such body of water is arranged in a chamber 65 between the motor chamber 6 and the pump chamber 5. The intermediate chamber 65 is formed within the shell 1 between the vertically spaced-apart partitions 3 and 4. A passage is provided from pump chamber 5 to the chamber 65, and advantageously such passage is concentric with the shaft 10; it is a passage formed by a clearance 30 between the shaft and the edge of the orifice in partition 3, through which the shaft 10 extends. When the pump is in operation, water is delivered not only through the outlet 14 but also through the clearance or opening 30. At the top of the chamber 65, that is, immediately below the partition 4, I provide an outlet, and such outlet consists in a circumferential series of ports 19. The water flowing through opening 30 fills the chamber 65 to the level of the ports 19, and the flow through opening 30, continuing unabated during pump operation, causes an overflow through the ports. Thus, a relatively large body of circulating water is maintained in thermal contact with the internal surface of the shell 1, while the water overflowing from such body passes through ports 19 and streams downward over the external surface of the shell. This flow of water over the inner and outer surfaces of the shell is effective to maintain the motor 7 at desired operating temperature; that is, the heat generated by the motor in service is drawn (by conduction) through the portions 10 and walls of the shell 1, into the water in contact with such walls. The flowing water carries the heat away from the shell, and the motor 7 is thus prevented from becoming overheated, without the aid of the usual air vents and fans that are manifestly objectionable in a structure such as this.

It is important to note that in the pump unit of this invention the frictional drag upon the rotating shaft 10 and impeller 40 is reduced to a minimum. The partition 4 supports a seal 21, through which the shaft extends with snug running fit. This seal is of double utility: it prevents water from entering the motor chamber 6; and it provides a bearing for the shaft immediately adjacent to the motor 7. Below the seal 21 neither the shaft nor the impeller is subject to mechanical friction; the impeller does not touch the walls of the pump chamber and the shaft does not touch the partition 3 through which it extends. By virtue of such organization friction losses are held to a minimum.

The delivery of the pump is regulated by means of a simplified but effective organization of a gate

22. The gate is adjustable upon the under surface of the floor 2, and in the range of its adjustment the area of the inlet 12 of the pump (and in consequence the output of the pump) may be regulated as desired. Such adjustment of the gate is effected by means of a rotary stem 23, borne in this case by one of the legs or feet 13, as shown. The stem 23, extending inward from such leg, is screw threaded and engages a threaded nut portion 22a on the gate, and the outer end of the stem is equipped with a knob 24 that facilitates the manual rotation of the stem, to shift the gate longitudinally of the stem and vary the effective area of the port 12. And for manifest reasons a screen 120 may be provided in (or over) such port or inlet of the pump. Within the terms and intent of the appended claims, various modifications are permissible.

I claim as my invention:

1. An unit toy structure including a pump 2 rotor and electric motor for driving the rotor arranged in vertically spaced-apart relation within a housing, said housing consisting in an elongate, dome-like shell adapted to stand, self-sustaining, on end in a shallow pool of water and 2 to extend above the surface of such pool, said shell enclosing said motor within its upper end, and including a pump chamber for said rotor within its lower end, an inlet and an outlet opening from such pump chamber through the wall 30 of such shell, together with an auxiliary outlet communicating with said pump chamber and arranged to deliver a cooling flow of water upon the external surface of said shell in the vertical interval between the pool surface and the portion of said shell in which said motor is enclosed. 35

2. An unit toy structure including a pump rotor and an electric motor for driving the rotor arranged in vertically spaced-apart relation within a housing, said housing consisting in an elongate, dome-like shell adapted to stand, self-sustaining, on end in a shallow pool of water and 40 to extend above the surface of such pool, said shell enclosing said motor within its upper end, and including a pump chamber for said rotor within its lower end, an inlet and an outlet opening from such pump chamber through the wall 45 of such shell, said shell being provided with a circumferential series of perforations above the surface of the pool in which the unit stands, 50 said perforations communicating internally of the shell with said pump chamber, with the effect that in service said pump delivers water through said perforations, and maintains upon the external wall of said shell, in the vertical interval 55 between the pool surface and the perforations, a flowing sheet of water that is adapted to dissipate the heat generated by said motor.

3. A motor-driven pump unit adapted to stand upon the bed of a pool of liquid, with the housing 60 of the pump provided with a transverse wall substantially paralleling, and spaced at an interval above, the surface of such bed, an inlet for liquid in such wall, and a valve adjustable substantially in the plane of the wall for regulating the effective area of such inlet. 65

HOWARD K. KLAUSS.
